UNITED STATES PATENT OFFICE.

ANDREW J. ZILKER, ALBERT L. TIDMARSH, AND CHARLES J. ARMSTRONG,
OF AUSTIN, TEXAS.

ELEVATING BRICK-CAR.

SPECIFICATION forming part of Letters Patent No. 757,710, dated April 19, 1904.

Application filed April 9, 1903. Serial No. 151,905. (No model.)

To all whom it may concern:

Be it known that we, ANDREW J. ZILKER, ALBERT L. TIDMARSH, and CHARLES J. ARMSTRONG, citizens of the United States, residing 5 at Austin, in the county of Travis and State of Texas, have invented a new and useful Elevating Brick-Car, of which the following is a specification.

The invention relates to improvements in 10 elevating brick cars or trucks.

The object of the present invention is to improve the construction of elevating brick cars or trucks and to provide a simple, inexpensive, and efficient car or truck designed 15 for use in a brick-yard for carrying bricks from a machine to a yard, kiln, or drier and from yard or drier to kiln or for otherwise handling bricks or other ware and adapted to be run beneath a pallet containing bricks and 20 elevated to raise the pallet from its supports to permit the same and its contents to be conveyed to the desired point.

A further object of the invention is to provide a car of this character which will have 25 its elevating frame arranged close to the ground to enable a large number of bricks to be conveniently loaded on it.

Also the invention has for its object to provide a brick-car in which the mechanism for 30 raising and lowering the upper frame may be operated at either end of the car to avoid turning the latter end for end and to obviate the necessity of providing turn-tables and transfer-cars for that purpose.

With these and other objects in view the invention consists in the construction and novel combination and arrangement of parts, hereinafter fully described, illustrated in the accompanying drawings, and pointed out in the 35 40 claims hereto appended, it being understood that various changes in the form, proportion, size, and minor details of construction within the scope of the claims may be resorted to without departing from the spirit or sacrificing any of the advantages of the invention.

In the drawings, Figure 1 is a side elevation of an elevating-car constructed in accordance with this invention, the upper frame being lowered. Fig. 2 is a plan view. Fig. 3 is 45 50 a side elevation, the upper frame of the brick-

car being elevated. Fig. 4 is a longitudinal sectional view, the parts being arranged as illustrated in Fig. 1. Fig. 5 is a horizontal sectional view. Fig. 6 is an enlarged detail sectional view illustrating the manner of 55 mounting the slideable wedges for raising and lowering the upper frame of the car. Fig. 7 is a transverse sectional view of the same. Fig. 8 is a horizontal sectional view on the line 8 8 of Fig. 7. 60

Like numerals of reference designate corresponding parts in all the figures of the drawings.

1 designates a lower or truck frame provided with front and rear bearings or journal-boxes for the reception of front and rear axles 2 of wheels 3, which may be flanged, as illustrated in Figs. 2 and 5 of the drawings, when the car is designed to run upon a track 4; but the flanges may be omitted and the car 70 may be constructed to run upon the ground similar to an ordinary brick-carrying truck. The bearings 5, which may be constructed in any desired manner, are preferably arranged to receive the axles at points between the 75 wheels, as shown, and the lower frame 1 is mounted directly upon the axles to provide a low truck to facilitate handling a large load of bricks or other material.

The lower frame 1 is composed of channel-iron sides 6 and connecting transverse end bars 7, provided with central outwardly-extending bifurcated arms 8, forming supports for operating-levers 9, hereinafter described, for raising and lowering an upper frame 10. 80 The channel-iron sides 6, which are provided with horizontal flanges 11, form guides or ways for movable antifriction devices which support reciprocating wedges 12. The antifriction devices consist of a series of antifriction rollers or wheels 13, arranged within an oblong frame 14 and connected with the same by pivots or spindles 15, extending through the rollers or wheels and through suitable perforations of the sides of the oblong frame, as 90 clearly illustrated in Figs. 6 and 7 of the drawings. The rollers are arranged upon longitudinal ribs or ridges 16, spaced apart, as clearly shown in Fig. 7, and forming tracks 95 for the antifriction devices, which are limited 100

in their movement by stops 17. The stops 17 preferably consist of L-shaped plates bolted to the bottoms of the channel-bars 6 and extending upward to provide abutments for the 5 ends of the oblong frame 14, as clearly shown in Fig. 6.

The wedge 12, which preferably consists of an open frame, has a lower horizontal edge or face to rest upon the rollers or wheels, and it 10 is preferably flanged at the bottom, as shown. The wedges present inclined upper faces 18 to antifriction rollers or wheels 19 of the upper frame 10, which is provided at opposite sides with channel bars or beams having 15 depending side flanges and presenting flat upper faces to receive the pallets. The antifriction rollers or wheels 19 are arranged within vertically-movable slides 20, consisting of flanged brackets and composed of opposite 20 side flanges, a vertical connecting flange or web, and a horizontal top flange which is bolted to the top frame, as shown at 21. The antifriction roller or wheel 19 is arranged between the side flanges of the vertically-movable 25 slide and is connected with the same by a spindle 22, which extends through the roller or wheel 19 and through the side flanges of the slide. The vertically-movable slides are arranged in ways of upright stationary guides 30 23, provided at the bottom with perforated webs or ears 24, which are bolted to the flanges 11 of the channel-bars of the lower frame. The upright guides are provided with parallel 35 vertical flanges 25, which receive the vertically-movable slides. The stationary guides extend across the ways formed by the channel-bars of the lower frame and are provided with openings or bifurcations at their bottoms to permit the wedges to move outward to the 40 position illustrated in Fig. 3 of the drawings.

When the wedges are moved outward from the position shown in Fig. 4 to that illustrated in Fig. 3, the upper frame is elevated and is adapted to lift a pallet from its support, and 45 when the wedges are moved inward the upper frame will be lowered to the position shown in Fig. 1 to enable the car to deposit a pallet upon suitable supports. The upper frame is also adapted to receive a suitable 50 platform or pallet for enabling bricks or other material to be loaded upon the car.

The upper faces of the wedges are provided with inner and outer or upper and lower seats 55 26 and 27, preferably curved, as shown, and adapted to receive the antifriction rollers or wheels 19 when the wedges are at the limit of their movement in either direction. The inner ends of the wedges are provided with upwardly-projecting ears 28, preferably formed 60 integral with plates 29 and adapted to receive transverse rods 30 for connecting the wedges at the opposite sides of the car. The plates 29 are secured by bolts 31 or other suitable fastening devices to the inner ends of the 65 wedges 12; but any other form of ear may be

employed. Each rod is connected with the end operating-levers 9 by bars 32 and 33, the bar 32 being located above the lower frame and extending outward from the inner end of the wedge to the upper end of the near lever 70 9. The other bar 33 extends inward from the inner end of the adjacent wedge and downward at an inclination and passes beneath the axle at the other end of the car, being connected with the lower end of the operating-lever at that end of the car. The operating-levers 9 are fulcrumed between their ends by pivots 34 or other suitable fastening devices in the bifurcations of the arms 8, and their terminals are perforated for the reception of 80 pivots 35 and 36 for connecting the levers with the outer ends of the bars 32 and 33. The outer ends of the inclined connecting-bars are angularly bent at 37 to enable them to clear the adjacent axles when the upper frame of 85 the car is elevated. The connecting-bars 32 and 33 are located at the center of the car, the inner ends of the connecting-bars 32 being forked to straddle the inner ends of the connecting-bars 33 and the latter being bent between their ends at 38 to clear each other.

The operating-levers 9 are provided at their upper portions with sockets 39 for the reception of a movable handle or bar 40, which is adapted to be transferred from one end of the 95 car to the other to enable the mechanism for raising and lowering the upper frame to be operated at either end of the car. This construction obviates the necessity of employing transfer-cars or turn-tables for turning the 100 car end for end. The handle or bar 40 is retained in the sockets by suitable catches 41, which may be constructed in any desired manner. When either operating-lever is oscillated, the wedges will be simultaneously reciprocated, and the shiftable antifriction devices which support the wedges will enable the latter to move freely inward and outward. The antifriction-wheels of the upper frame also permit the latter to be raised with a minimum amount of friction. The weight of the 110 upper frame and the load of the car resting upon the upper seats will retain the parts in the position illustrated in Fig. 3 of the drawings, and it is unnecessary to provide any locking mechanism for preventing the wedges from accidentally moving inward. The construction for raising and lowering the upper frame also permits a low truck or car to be constructed, thereby increasing the carrying capacity, as bricks can be conveniently loaded only to a certain height.

Having thus fully described our invention, what we claim as new, and desire to secure by Letters Patent, is—

1. In a car or truck of the class described, the combination of a lower frame provided with wheels and having vertical guides, an upper vertically-movable frame provided with vertical slides arranged in the guides of the 130

lower frame, and a shiftable wedge for raising and lowering the upper frame, substantially as described.

2. In a car or truck of the class described, the combination of a lower frame provided with wheels, an upper vertically-movable frame, shiftable wedges mounted on one of the frames and operating against the other to raise and lower the upper frame, operating-levers located at the ends of the car, and means for connecting the operating-levers with each of the wedges, whereby the upper frame may be raised and lowered from either end of the car, substantially as described.

15 3. In a car or truck of the class described, the combination of a lower frame, a vertically-movable frame, a shiftable wedge, and a movable antifriction device interposed between the wedge and one of the frames, substantially as described.

25 4. In a car or truck of the class described, the combination of a lower frame, an upper frame, a reciprocating wedge, and a shiftable antifriction device movable with the wedge and interposed between the same and one of the frames, substantially as described.

30 5. In a car or truck of the class described, the combination of a lower frame, an upper frame, a reciprocating wedge for raising and lowering the upper frame, and a shiftable antifriction device interposed between the wedge and one of the frames and comprising a series of antifriction rollers or wheels spaced apart and connected with one another, substantially as described.

35 6. In a car or truck of the class described, the combination of a lower frame, an upper frame, a reciprocating wedge for raising and lowering the upper frame, and a shiftable antifriction device interposed between the wedge and the frame and comprising a series of antifriction rollers or wheels spaced apart, and a frame receiving the rollers or wheels and connected with the same, substantially as described.

45 7. In a car or truck of the class described, the combination of a lower frame, an upper frame provided with an antifriction device, a reciprocating wedge having an inclined face receiving the antifriction device of the upper frame, and a shiftable antifriction device interposed between the wedge and the lower frame and movable with the former, substantially as described.

55 8. In a car or truck of the class described, the combination of a lower frame having a guide, an upper frame having a slide arranged in the guide, an antifriction-wheel carried by the slide, and a reciprocating wedge mounted on the lower frame and having an inclined upper face to receive the antifriction-wheel, substantially as described.

65 9. In a car or truck of the class described, the combination of a lower frame, an upper frame having an antifriction-wheel, and a re-

ciprocating wedge presenting an inclined upper face to the wheel and provided at the upper portion with a seat to receive the wheel, substantially as described.

10 10. In a car or truck of the class described, the combination of a lower frame, an upper frame having an antifriction-wheel, a wedge mounted on the lower frame and having an inclined upper face and provided with inner and outer curved seats, and means for reciprocating the wedge, substantially as described.

15 11. In a car or truck of the class described, the combination of a lower frame having a way and provided with ribs forming rails, stops located at the ends of the ribs, a shiftable antifriction device comprising rollers or wheels arranged on the ribs, and an approximately oblong frame connecting the rollers or wheels, an upper frame, and a reciprocatory wedge mounted upon the shiftable antifriction device and receiving the upper frame, substantially as described.

20 12. In a car or truck of the class described, the combination of a lower frame, a guide mounted on the lower frame and provided with parallel flanges and having a bifurcated lower portion, an upper frame having a slide arranged in the said guide, and a wedge for raising and lowering the upper frame, said wedge being movable through the opening of the guide, substantially as described.

25 13. In a car or truck of the class described, the combination of a lower frame, an upper frame, shiftable devices for raising and lowering the upper frame, operating-levers fulcrumed between their ends and located at the ends of the car or truck, short connecting-bars extending from the upper arms of the operating-levers to the adjacent shiftable devices, and the long connecting devices extending from the lower arms of the levers and crossing at the center of the car or truck and connected with the shiftable devices, substantially as described.

30 14. In a car or truck of the class described, the combination of a lower frame, a vertically-movable upper frame, shiftable wedges for raising and lowering the upper frame, operating-levers fulcrumed between their ends and located at the ends of the car or truck and provided with sockets adapted to receive a handle or bar, and the upper and lower connecting means extending from the arms of the levers to the wedges, the lower connecting means being crossed at the center of the car or truck, substantially as described.

In testimony that we claim the foregoing as our own we have hereto affixed our signatures in the presence of two witnesses.
